UNITED STATES PATENT OFFICE.

MORTIMER JAY BROWN, OF NIAGARA FALLS, NEW YORK, ASSIGNOR, BY MESNE ASSIGNMENTS, TO THE PACIFIC R & H CHEMICAL CORPORATION, OF LOS ANGELES, CALIFORNIA, A CORPORATION OF CALIFORNIA.

VALVE.

Application filed August 21, 1922. Serial No. 583,134.

To all whom it may concern:

Be it known that I, MORTIMER JAY BROWN, a citizen of the United States, and resident of Niagara Falls, in the county of Niagara and State of New York, have invented certain new and useful Improved Valves, of which the following is a specification.

My invention is specifically an improved 10 pop-off valve and pertains particularly to equipment for handling volatile liquids. The particular object of my invention is to provide a pop-off valve that cannot trap and hold gases when used for handling 15 liquids. Other objects of my invention and its utility will be apparent from the detailed description to follow and the drawings that form part of this specification.

Fig. 1 shows the location of the valve 20 with reference to the other parts of the apparatus, such as the pump, supply tank, and nozzle.

Fig. 2 is a longitudinal section through 25 the valve,

Fig. 3 is a section on the line 1--2 of Fig. 2.

In my co-pending application No. 501,553, there is described a machine for handling volatile liquids, particularly liquid hydrocyanic acid. It is represented by Fig. 1, and consists essentially of a tank A, a measuring cylinder B, a piston C, and a device D for limiting the up-stroke of the piston. The down-stroke of the piston is limited 35 by a contact with the metallic bottom of the measuring cylinder. This measuring pump delivers the precise amount of liquid represented by the length of the piston strokes through pop-off valve E, pipe F 40 and nozzle G. On the down-stroke valve E opens. On the up-stroke it closes promptly with the result that pipe F and nozzle G are always full of the liquid that is being employed. The object of valve E is to prevent liquid flowing from the tank A down 45 through cylinder B and out through nozzle G when piston C is being raised. Inasmuch as the height of the liquid is seldom more than twelve inches above valve E, an ordinary ball check with a light-acting spring is sufficient to prevent the liquid from escaping. The valves that have ordinarily been used for this machine have been simple ball checks modified by the addition

of a vertical chimney-like chamber in 55 which operates a long spring of gentle action, pressing constantly upon the ball which in turn is pressed against the seat of the valve. Machines as thus constructed were not found to give entirely satisfactory 60 service due to the fact that at the end of each stroke there was a small but nevertheless undesirable spurt of liquid from the nozzle. It was eventually found that the cause of this spurt was the fact that there 65 was trapped in the chimney-like chamber containing the spring, a pocket of air or other gas which acted as a cushion, being compressed during each down-stroke and expanding at the end thereof. For reasons 70 of convenience in construction and operation and for other reasons pertaining to certain materials that might be used in the machine it was found undesirable to invert the check valve or even to place the 75 chimney in a horizontal plane. It therefore became necessary to devise a valve that would have all of the desirable characteristics of the ones that had been used, but without the fault of trapping gases in the 80 manner indicated.

The piston C in application S. N. 501553, filed September 19, 1921, for apparatus for measuring and discharging liquid, is provided with a valve mechanically actuated 85 by the piston rod in advance of movement of the piston for avoiding any suction or reduction in pressure on the liquid, which, being hydrocyanic acid, vaporizes at a low temperature and on reduction of pressure. The pump is charged by gravity through the holes K in the barrel and the piston C is provided with a passageway S there-through controlled by relative movement of the piston rod T.

My invention specifically is a valve that cannot trap and retain gases when being used in a machine such as the one described. This valve is shown in vertical cross section in Fig. 2 wherein H is the seat, I is the ball, J is the vertical chimney and K is the spring. Liquids passing the valve are forced in through L and H and escape at M. When liquid has entered the valve through L and H it may be forced out, 100 either downwardly into the annular groove surrounding the seat and thence through the tube, shown by dotted lines in Fig. 2, or it

- may pass upward through the chimney J down through the small tubular opening N to the annular groove and out as before. Some of the liquid takes each path. Whenever liquid carrying entrained gases passes into the valve, the gases immediately rise in the chimney J, pass down the small tubular opening N and are again entrained in the escaping liquid and pass out at M without any appreciable delay in the passage. The passageway from the lower portion of the chimney J surrounding the ball I to the annular groove surrounding the seat H is sufficiently constricted so that some of the liquid is continually forced up the chimney J and down the small passage N, yet large enough to permit some of the liquid to flow through this constricted portion.
- 20 Fig. 3 shows a cross section of the chimney, on the line 1—2 of Fig. 2. I have found that with a valve embodying this principle a chimney of any desired height can be used and therefore a spring of any desirable characteristics, and that without fail the chimney frees itself of the gases immediately after they are introduced into the valve. Its action is entirely automatic, requiring no care whatever on the part of the operator and it cannot cease to function unless the valve becomes so foul with dirt that passage G is entirely obstructed.
- 25 It is obvious that a disc may be substituted for a ball. Also, since the spring as shown operates on a vertical axis, it can be replaced by a cylindrical metallic slug of sufficient weight to exert the same pressure as a spring. I do not therefore limit myself to a spring nor to any one of the well known methods of exerting pressure on or by the valve. The valve will function well if the chamber that holds the spring is inclined away from the vertical. It may, in fact, be placed at an angle, although when placed on a horizontal axis my invention ceases to function.
- 30 From the drawing it will be seen that the closed chamber above the valve seat is threaded onto the body portion containing the inlet and outlet passages, and therefore it will be seen that this closed chamber may be removed to afford access to the valve seat for cleaning.
- 35 The combination of a pump containing a positively actuated valve in the piston, which creates no suction on the liquid, with the pop-off valve described in detail in this application, has been covered by claims in my divisional application S. N. 687,224 for measuring and spraying apparatus for a volatile fumigant, filed January 19, 1924, while the claims in the present application are limited to the pop-off valve per se.
- 40 I claim:
- 45 1. The combination with a pop-off valve, of a seat therefor, a closed chamber above said valve seat, a supply passageway leading to said valve and controlled thereby, an outlet passageway leading from said chamber and provided with a constricted portion, 70 and another passageway from the top portion of said chamber connected to said outlet passageway beyond its constricted portion.
2. The combination with a valve for liquids, of a seat therefor, a closed chamber above the valve seat, a supply passageway leading to the valve and controlled thereby, an outlet passageway leading from the lower portion of said chamber adjacent said seat, a passageway leading from the upper part of said chamber and connected to said outlet passageway, and means to cause a portion of the liquid to pass through said passageway from the upper part of the 85 chamber.
3. In a valve, the combination with substantially horizontal inlet and outlet passageways thereto and from, of a valve and seat, a substantially vertical chamber 90 removably surrounding the valve seat, an outlet from the lower part of said chamber, and means for removing any gases from the upper part of said chamber.
4. The combination with a valve for liquids, of a seat therefor, a closed chamber above said seat and larger than said valve to enable liquid to rise in the chamber, 95 ast said valve when open, a supply passageway leading to said valve and controlled thereby, an outlet passageway leading from said chamber and provided with a constricted portion therein, a passageway leading from the upper portion of said chamber and connected to the outlet passageway beyond said 100 constricted portion, said constricted portion being of such a size as to cause some of the liquid to pass through the passageway leading from the top of the chamber and yet enable some of the liquid to pass through 105 the constricted portion of the outlet passageway.
5. The combination with a valve for liquids, of a seat therefor, a closed chamber above the seat, a passageway leading from the top of said chamber to below the valve seat, and means for causing at least a portion of the liquid supply to pass through said passageway.
6. The combination with a valve for liquids, of a seat therefor, a closed chamber above said valve seat, and a plurality of small outlet passageways leading from said chamber, at least one of said passageways leading from the upper portion 115 of said chamber for removing any gases along with the liquid passing therethrough.
7. The combination with a valve, of a seat therefor, a liquid supply passageway controlled by the valve, an elongated closed

chamber above said valve seat, a spring in cooperation with said chamber and valve, an outlet passageway leading from the lower portion of said chamber, another passageway leading from the upper part of said chamber and connected to the outlet passageway, and means for causing a portion of the liquid to pass through the passageway from the upper part of the chamber.

Signed at Niagara Falls, in the county of Niagara and State of New York, this 14th day of August A. D. 1922.

MORTIMER JAY BROWN.
